UNITED STATES PATENT OFFICE.

WILLIAM R. BAKER, OF CHICAGO, ILLINOIS, ASSIGNOR TO THE McCORMICK HARVESTING MACHINE COMPANY, OF SAME PLACE.

BUNDLE-CARRIER FOR GRAIN-BINDERS.

SPECIFICATION forming part of Letters Patent No. 361,977, dated April 26, 1887.

Application filed March 12, 1885. Serial No. 158,622. (No model.)

To all whom it may concern:

Be it known that I, WILLIAM R. BAKER, a citizen of the United States, residing at Chicago, in the county of Cook and State of Illinois, have 5 invented certain new and useful Improvements in Bundle-Carriers for Grain-Binders, of which the following is a specification.

In that type of bundle-carriers which swing or tilt transversely to the line of advance of the 10 machine, so as to open a gap between themselves and the binder-decking or discharge-chute, through which gap the load is deposited on the ground, difficulty has been experienced in making a clean and compact dump, owing 15 to the fact that the floor of the carrier remains parallel with the advance, and being, as a rule, composed of slats, these catch the sheaves and twist them around and leave them lying awry and scattered as the machine passes on. This 20 I propose to remedy by supporting and tilting the carrier on different axes at front and rear, which is most effectively done by suspending it on pivoted arms or bails, the rear arm being the longer, so that when swung out to discharge 25 a load the rear of the carrier will be taken farther from the binder than the front, leaving a wider gap at the rear, whereby the onward movement of the machine will tend to take the flooring away from the sheaves discharged, in- 30 stead of scraping it past them. With such carriers, also, it requires an expenditure of considerable force to open them for the discharge of the accumulated load, and if this is thrown upon the driver, coupled with the other 35 labors incident to the management of the machine, a few hours' work exhausts him. For this reason various efforts, attended with more or less success, have been made to operate the carrier by power furnished by the draft of the 40 machine.

My improvement, so far as it relates to this feature, consists in connecting the lever-arm by which the carrier is swung with a rack-bar, which engages with a pinion on the harvester 45 to throw the carrier open, and by means of a treadle and friction-brake may be retained against the stress of the carrier after said pinion has ceased to actuate it until the load is entirely cleared.

50 In the drawings, Figure 1 is a top plan view

of so much of a harvester (the binding attachment being omitted) embodying my invention as is necessary to an understanding thereof. Fig. 2 is a rear elevation of the parts shown in the preceding figure; Fig. 3, a diagrammatic elevation from the stubble side of the machine; Figs. 4, 5, and 6, enlarged details of the rack-bar and accessory mechanisms. Fig. 7 represents in rear elevation means whereby the special carrier invented by me may be operated 60 by hand, and Figs. 8 and 9 are respectively a side elevation and a section of the preferred construction of the mechanism for operating the rack-bar.

A represents the elevator-frame, which does 65 not or need not differ from the usual shape.

B is the rear sill, and B' the front sill; C, the end sill on the stubble side; D and D', the lateral beams constituting the wheel-frame, and E the main wheel.

F is the binding-table or decking, prolonged by a discharge-chute, F; but I have shown no binding mechanism, as my invention is irrespective of any particular type of automatic binder, and the parts already enumerated are 75 to be taken only as exponents of a very general class.

Suitably secured adjacent to the front sill, and parallel therewith, is a bar, G, projecting out from the machine and having at its extreme end a low standard, g, provided with a bearing near its top; but this standard may be omitted if it is seen fit to place the bar at a higher elevation. From the rear struts of the elevator-frame, or from others suitable support, 85 projects another bar, G', in a plane parallel with the first, but so that its outer end is higher than the outer end of that, and this last-named bar has at said outer end a journal-bearing, g', still considerably higher than the 90 journal-bearing in the standard on the other.

The carrier H may be constructed in any suitable manner and of any suitable material. It is shown for the purposes of this case as composed of parallel metal slats, h, pointing 95 in toward the harvester, riveted to a cross-bar, h', and at the outer ends turned up and united by a strap, h'', and this is perhaps the lightest and most durable form in which it can be embodied. At both front and rear it has verti- 100

cal arms h^3 , both rigidly secured to the cross-bar, and therefore directly opposite each other, but the rear arm being somewhat longer than the other. These arms or bails carry pivot-
5 pins at such relative height on each that when set into the bearings at g and g' , respectively, the carrier will be supported by them horizontally so long as it is in the receiving position.

10 To the rear bail is secured a lever-arm, i , with which is pivotally connected one end of an operating bar or rod, I , extending to the elevator and there either provided with a hand-hold, as in Fig. 7, that the driver may open 15 the carrier by main strength, or else with a rack, i' , for engagement with a pinion, whereby it may be operated by the draft of the team. Other means may be adopted to open a carrier of this construction, it being understood, 20 of course, that it is intended to gravitate back to receiving position. It is evident that with this construction, whenever the carrier is opened, its rear supporting-bar will make the longest sweep, taking that side of the carrier 25 farther from the binder than the other and lifting it higher—that is, to a level with its rear pivot. A gap will thus be caused between the binder and carrier and between the ground and the ends of the carrier-slats that 30 increases constantly in dimensions from front to rear, so that the onward movement of the machine will take the carrier from the pile of sheaves as a housewife draws a mold from the jelly.

35 In order to utilize the power of the team in operating the carrier, whether it swings on two axes or but one, a pinion on some constantly-driven shaft of the harvester, convenient for the purpose, is arranged to be engaged with 40 the rack-bar I , either intermittently or permanently. In the first case the pinion will be keyed to its shaft and run therewith; but in the second it will be loose on the shaft and clutched thereto only when the carrier is to 45 be opened. One arrangement is indicated in the first six figures of the drawings and the other in the eighth.

Proceeding to describe the first-indicated method: In harvesters and binders manufactured by the McCormick Harvesting Machine Company the reel is usually driven by a telescopic tumbling-shaft, K , extending from the rear, where it receives motion through a sprocket-wheel, K' , over the foot plank k , to its 50 connection with the reel-supports, as shown, for instance, in Letters Patent No. 270,910, granted January 23, 1883, to said company as assignee. Upon the rear member of this shaft, which is mounted in fixed bearings, I 55 key a pinion, k' , in such position that it will come immediately above the rack-bar, which is so confined in a guide loop or keeper, k^2 , that it may be moved toward or from the pinion to bring it into or throw it out from engagement therewith. A strong plate-spring, 60 l , with its effective face parallel with and

pressing upon the teeth of the rack, serves not only to constantly urge it away from the pinion and to the bottom of the guide-loop, but also as a brake whereby the rack-bar may be 75 temporarily held from retrogression after being disengaged from the pinion, to keep the carrier open until its load is entirely cleared. A treadle or foot-lever, L , is pivoted to one of the brackets l' , which carry the bearings for 75 the tumbling-shaft, or to any other convenient support above the foot-blank, so that it may be operated by the driver in his seat. At the rear end this lever is bent down and brought beneath the rack-bar opposite the pinion, or 80 thereabout, and is provided with an anti-friction roll, l^2 , for contact with said bar. By depressing the lever the bar will be raised against the force of the spring and brought into engagement with the pinion, which will instantly act to draw it in, thus swinging the carrier out and discharging the load. When the carrier is fully opened, the driver will release the treadle sufficiently to disengage it 85 from the pinion, but will still hold it against 90 the spring, now acting as a brake, with sufficient force to prevent the carrier from closing until the load has fully escaped.

In the second method, as illustrated in Figs. 8 and 9, the spring is dispensed with, the 95 rack-bar is confined closely in its loop and in constant engagement with its pinion, the pinion is mounted loosely upon its shaft, and has a friction-disk, m , on its rear face, while a counter-disk, m' , is keyed to the shaft, so that 100 the pinion will be clutched to said shaft whenever jammed against the counter-disk with sufficient force. On a bracket adjacent to the hub of the pinion is pivoted a short lever, N , having a collar, n , loosely embracing the shaft 105 and arranged to be brought against the end of the pinion-hub to press it toward the disk. A bell-crank treadle, O , is pivoted to a low standard on the foot-board and connected with the power end of lever N by means of the 110 link O' . To insure a steady frictional grip, a spring, o , is interposed between the link and the treadle-arm, to which it is connected, and a nut provided to adjust this spring.

As thus far described, these parts are sufficient to insure the action of the pinion upon the rack-bar and the retention of the latter while the load is being cleared, since according to the degrees of pressure upon the friction-clutch the carrier will be opened or merely 115 held open, or allowed to close, the clutch either driving the pinion or acting as a brake to hold it and the rack-bar stationary, or releasing it altogether; but as it sometimes happens that the bundle-carrier is accidentally 120 tilted, I propose to lock it against movement until the pinion is clutched to its shaft. For this purpose a fork is made in the link, one arm, o^2 , of which is hooked and passes through an elongated slot in the end of the lever N , 125 while the other, o^3 , is passed through a guide 130 in the standard which supports said lever, and

- its end brought immediately behind the end of the rack-bar to prevent it from moving inward until the treadle is depressed, which action will first withdraw the locking-arm O^2 5 without disturbing the lever N , owing to the play of the other arm in the recess, and then bringing said latter arm against the inner side of the recess will actuate the lever and cause the engagement of the friction clutch.
- 10 The forked link is constantly under stress to return to the locking position through the instrumentality of a spring, P , pressing on the end of the hooked arm, so that the instant the treadle is released it will fly back to that position unless otherwise restrained. Such restraint is afforded, so long as the carrier is open, by the contact of the locking-arm with the side of the rack-bar, which bars its passage; but as soon as the end of this bar is reached, 15 which will be at the moment the carrier is entirely closed, the restraint ceases and the locking-arm shuts in past said end, as before.
- Having thus described my invention, what I claim as new, and desire to secure by Letters Patent, is—
- 20 1. The combination, substantially as hereinbefore set forth, with the harvester-frame, of a bundle-carrier pivotally suspended at the stubble end thereof by means of arms or bails, the rear one of which is the longest.
- 25 2. The combination, substantially as hereinbefore set forth, with the harvester-frame, of a bundle-carrier pivotally suspended from supports on said frame by arms, the rear arm being the longest, and a lever-arm and draw-bar whereby said bundle-carrier may be swung out to discharge its contents.
- 30 3. The combination, substantially as hereinbefore set forth, of the beams extending from front and rear of the harvester-frame, the standard on the front beam, and the bearing on the rear beam at a higher elevation than a like bearing in said standard, the bundle-carrier having a short arm or bail in front pivoted in 35 said standard, and a long arm at rear pivoted in the bearing of the beam, the lever-arm fixed to said longer arm, and the draw-bar extending from the end of the lever-arm to the elevator-frame.
- 40 4. The combination, substantially as hereinbefore set forth, of a bundle-carrier pivoted in supports from the harvester, a lever-arm for swinging said carrier on its supports to discharge its load, a rack-bar connected with said lever-arm, a pinion which operates the rack-bar to open 45 the carrier, and a stop to prevent accidental opening of the carrier, adapted to be thrown into action to dog the rack-bar when the carrier closes and to be withdrawn immediately preceding the effective action of the pinion.
- 50 5. The combination, substantially as hereinbefore set forth, with a bundle-carrier pivoted in supports from the harvester-frame, of a lever-arm attached to said carrier, whereby it may be swung upon its supports, a rack-bar attached to said lever-arm, a pinion mounted 55 loosely on a driven shaft of the harvester, a friction-disk on the pinion, a friction-disk
- fixed to said shaft, and a foot-lever or treadle whereby said pinion may be brought against the fixed disk with varying force to engage with the shaft in order to open the carrier, 70 and to be held stationary to keep the carrier open.
6. The combination, substantially as hereinbefore set forth, of a bundle-carrier pivoted in supports from the harvester-frame, a lever-arm attached to said carrier, whereby it may be swung or tilted in its supports, a rack-bar connected with said lever-arm, and a pinion upon the reel driving-shaft of the harvester to operate said rack-bar.
7. The combination, substantially as hereinbefore set forth, of a bundle-carrier pivoted in supports from the harvester-frame, a lever-arm attached to said carrier, whereby it may be swung or tilted on its pivots, a rack-bar 85 connected with said lever-arm, a pinion provided with a friction-disk and mounted loosely upon the reel driving-shaft and constantly engaged with said rack-bar, a friction-disk fixed on the shaft alongside of that on the pinion, and a foot-lever or treadle whereby the said pinion may be brought against the disk on the shaft with varying force to engage with the shaft, or to be held stationary, or to be released altogether, for the purpose stated.
8. The combination, substantially as hereinbefore set forth, of the carrier pivotally suspended from its supports by arms or bails of different lengths, the lever-arm attached to the longer arm, the rack-bar connected with said lever-arm, the pinion engaging with said rack-bar and running loosely on the reel driving-shaft, the friction-clutch arranged for engagement with said pinion, and the foot-lever for causing such engagement.
9. The combination, substantially as hereinbefore set forth, of the pivoted carrier, the lever-arm by which it is swung on its pivot, the rack-bar connected with said lever-arm, the pinion which operates the rack-bar to open 100 the carrier, and a stop to prevent accidental opening of the carrier, adapted to be thrown into action to dog the rack-bar when the carrier closes and to be withdrawn immediately preceding the effective action of the pinion.
10. The combination, substantially as hereinbefore set forth, of the pivoted carrier, the lever-arm by which it is swung upon its pivot, the rack-bar connected with said lever-arm, the pinion constantly engaged with said rack-bar, a clutch whereby it may be connected to its shaft, a locking-bolt arranged to be projected past the end of the rack-bar when the carrier is closed, to dog it and prevent opening, and means whereby said bolt is withdrawn 115 whenever the pinion is thrown into engagement with its clutch.
11. The combination, substantially as hereinbefore set forth, of the pivoted carrier, the lever-arm by which it is swung upon its pivot, the rack-bar connected with said lever arm, the loose pinion constantly engaged with said

rack-bar and having a friction-disk, the reel driving-shaft and friction-disk fast thereon, the lever pressing on the hub of the pinion to force it against the fast disk, the forked link 5 hooking by one arm into an elongated recess in the power end of the lever and having the other arm formed as a bolt to be projected

past the end of the rack-bar, and the treadle to which the link is connected at its forward end.
